AUXILIARY ROTARY PRINTING ATTACHMENT FOR PRINTING PRESSES

William M. Kelly, Westfield, N. J., assignor to
American Type Founders Company, Elizabeth,
N. J., a corporation of New Jersey

Application September 8, 1933, Serial No. 688,693

21 Claims. (Cl. 101—215)

This invention relates to auxiliary printing devices and more particularly to attachments of this character which may be applied to printing presses of various kinds in order to obtain a plurality of impressions during a single cycle of operation of the press; each of such impressions to be made in a different color if so desired.

The general object of the invention is to provide a novel and improved printing attachment of this class which is of sturdy construction, of efficient and compact arrangement, and capable of ready installation, adjustment and operation.

Although in its broader aspects, the invention may include printing mechanism of general application, in its preferred embodiment, the invention contemplates the provision of a rotary auxiliary printing attachment for a two-revolution bed and cylinder press such as the well-known Kelly press. Means are provided for intermittently and automatically moving the printing member of the attachment into and out of contact with the impression cylinder; such contact preferably being effected during the normal printing stroke of the press cycle and prior to the taking of an impression from the form on the reciprocating bed. Positively actuated means are also provided for moving the rolls or cylinders of the auxiliary printing attachment to an inoperative position in case it is desired to operate the press as a single impression machine.

My novel attachment may be arranged for either offset or relief printing, and practical embodiments are disclosed in the present specification and accompanying drawings exemplifying both of these arrangements. For certain kinds of color work, the offset method may be especially preferred. In this connection, my invention has the further object of providing certain convenient arrangements and adjustments of the blanket and plate cylinders or their counterparts in the offset attachment.

Other objects and features of novelty will be apparent from the following specification when read in connection with the accompanying drawings in which certain embodiments of my invention are illustrated by way of example.

In the drawings:

Figure 1 is a view in side elevation of a rotary offset auxiliary printing attachment embodying the principles of my invention, and applied to a bed and cylinder press; the latter being illustrated partly in diagram;

Figure 2 is an enlarged view in side elevation of the same attachment and a portion of the press to which it is applied;

Figure 3 is a fragmentary vertical cross sectional view of the attachment taken on line 3—3 of Figure 2;

Figure 4 is a fragmentary horizontal cross sectional view taken on line 4—4 of Figure 2;

Figure 5 is a somewhat diagrammatic view in side elevation of the attachment, illustrating certain adjustments of the rolls thereof;

Figure 6 is a view in side elevation on an enlarged scale as compared with Figure 1, of an attachment of this general type designed for direct printing; and

Figure 7 is an end view of the multiple cam member employed for actuating various parts of the press and attachment in proper sequence and duration.

In Figures 1 and 2 of the drawings, the auxiliary offset printing attachment is designated generally by the numeral 10, and includes a pair of side frames or brackets 11, each of which is suitably secured to the side frames 12 of the printing press designated generally by the numeral 15. The side frames of the attachment 10 are connected to each other by certain shafts or cross rods which extend from one side of the press to the other, and comprise operative portions of the attachment. Suitable tie rods or other additional cross bracing means may be employed if desired.

The press, which is illustrated in the drawings for an exemplary embodiment of the invention, is of the well-known Kelly type and is disclosed in greater detail than in the present application in my Patent No. 1,336,841 and others referred to below. This press is of the two-revolution bed and cylinder type, but it is conceivable that the auxiliary printing attachments forming the subject of the present invention may be applied to presses of other types within the scope of certain of the broader claims.

The press 15 is provided with a base frame or support 16 which houses the greater portion of the driving mechanism and serves to support the superstructure of the press which comprises the side frames 12, which carry the reciprocating bed 17, and the sheet feeding portion 18 of the press located at the right hand end thereof as seen in Figure 1. Inking mechanism 19 is provided in connection with the reciprocating bed 17 and is driven by suitable gearing connected in a conventional way with the main source of power for the press.

The impression cylinder 20 is carried by the shaft 21 which is mounted in suitable bearings 22 provided in the usual brackets 23 supported

by the side frames of the press. On one end of the shaft 21,—the remote end as seen in Figures 1 and 2—there is secured a gear or pinion 25 by means of which the driving force is transmitted to the impression cylinder. In this type of two-revolution press, means must be provided for lowering and raising the impression cylinder into and out of printing contact with the reciprocating bed 17. This mechanism may be of any suitable type, but is preferably of the general type illustrated and described in Patent No. 1,096,036 issued to me on May 12, 1914. Certain portions of this mechanism are shown in Figure 1 and comprise the rocker arm 26, the link 27 and the cam lever 28. The last named element is guided within the cam groove 29 provided in the multiple cam member 30.

The supply of sheets to be printed is carried at the right hand end of the press, the pile of sheets being elevated in a well-known manner so that individual sheets may be fed from the top thereof by suitable mechanism carried by the feeding portion 18 of the press. The sheet feeding means includes the feed table 32 and the conveyor arms 33, the former being pivoted to the frame 18 as at 34 and the latter adjacent the cam shaft 35. The general arrangement of this feeding means together with the sheet detectors and certain other details, are illustrated and described in my Patent No. 1,787,532 of January 6, 1931. The sheet detector referred to is shown at 36 in the drawings and is suitably connected with the sheet feeding mechanism, a portion of which is shown at 37.

Since the auxiliary printing device occupies the places where the front sheet stops and margin rolls are generally located, these elements are disposed, in accordance with the present invention, upon the opposite side of the impression cylinder 20 and are associated with the pivoted feed mechanism of the press. The margin roll is shown at 38 and is carried by the T-rail 39 upon which it may be adjusted laterally of the feed board 32. The front stop 40 is carried by the lever arm 41 which is pivoted at 42 and is adapted to be intermittently raised by the operating mechanism comprising the crank or rocker 43, the link 44, and the cam lever 45. The cam lever 45 is operated by the cam 46, which is secured to the cam shaft 35 which also carries other operating elements associated with the sheet feeding end of the press.

As the sheets are successively fed to the impression cylinder 20 by the means just described, they are seized by the grippers 48 at the proper instant and are carried around the impression cylinder to be printed. Suitable mechanism for actuating the grippers 48 is provided and may follow the disclosures in the W. M. Kelly Patents 1,092,998, April 14, 1914; 1,227,450, May 22, 1917, or 1,339,654 of May 11, 1920. A portion of this mechanism is shown in Figures 1 and 2 of the drawings and includes the cam lever 49 which is operated by the lateral cam surface 50 associated with the multiple cam member 30. The lever 49 is pivoted at 51 and is provided at its upper end with a bifurcated yoke 52 suitably connected with the gripper actuating mechanism disposed within the impression cylinder 20.

Suitable sheet delivery mechanism is provided at the left hand side of the press as shown in the drawings, and a portion of which is indicated at 54. In order to remove the printed sheet from the impression cylinder 20, there are provided stripper fingers 55 which are actuated by

the rocker arm 56 and the link 57, which are connected to the cam lever 58. One end of this lever is disposed in rolling contact with the cam surface 59 associated with the multiple cam member 30.

My novel rotary auxiliary printing attachment as applied to the press for effecting offset or planographic work comprises the plate cylinder 60 and the blanket cylinder 70 which are carried respectively by the shafts 62 and 63. The opposite ends of the shaft 62 are mounted in the bearings 64 which are carried by the vertically disposed sliding blocks 65. Upon one end of the shaft 62 there is secured a gear 67 which normally meshes with a corresponding gear 68 carried by the end of the blanket cylinder shaft 63. This gear 68 in turn meshes with the impression cylinder gear 25 in the normal operation of the printing attachment. The slides 65 are disposed within suitable openings in the side frames 11 of the auxiliary attachment and are retained by the inner and outer guide flanges 69. The slides 65 which carry the plate and blanket cylinders are arranged for vertical movement so that these cylinders may be brought into and out of printing contact with the impression cylinder. The mechanism for accomplishing this vertical sliding movement includes the rocking levers 72 which are secured upon the opposite ends of the shaft 74 which extends from one side of the attachment to the other. Each of the levers 72 is provided with bifurcated ends 75 which embrace the pin 76 which is secured to the adjacent slide 65. The lever 72 on one side of the attachment is provided with an extension 77 which is pivotally connected with link 78 which, in turn, is pivoted to one end of the rocking cam lever 79, which is pivotally secured to the lower projecting ends of one of the side frames 11 as at 80. The opposite end 81 of the cam lever 79 is disposed in rolling contact with the cam surface 85 on the multiple cam 30. This cam surface 85, which is the only one associated with the auxiliary attachment, may be formed as an integral part of the cam member 30 or may be separately applied to the multiple cam member originally provided with a press of this type. The cam surface 85 is, of course, so shaped as to cause the slides 65 to reciprocate at the proper times during the cycle of operation of the press.

Preferably the plate and blanket cylinders are moved downwardly so that the blanket cylinder makes a printing impression upon the sheet carried by the impression cylinder 20 just after the grippers 48 have seized the sheet and the impression cylinder has begun to descend to effect printing contact with the bed 17. Thus the offset impression made by the blanket cylinder 70 is effected first and the sheet is then carried around the impression cylinder to receive the impression from the form on the bed. The blanket cylinder remains in contact with the impression cylinder during the necessary portion of its rotation and then is raised during the remainder of the complete double revolution cycle of the press. The vertical movement of the cylinders 60 and 70 is of the magnitude of only approximately $\frac{1}{8}$ of an inch and this is insufficient to disengage the teeth of the gears 25 and 68, and thus the cylinders of the attachment continue to rotate during the entire operation of the press. Thus they may be continually inked and dampened during both revolutions of the impression cylinder. Mechanism for effecting these operations will be described further in the present specification.

In order to regulate the pressure of the impression in the auxiliary printing couple, there is provided an adjustable mechanism comprising rods 87 which are pivotally secured as at 88 upon each of the side frames 11. The upper ends of these shafts are adapted to project loosely through openings in the pivoted lugs 90 carried by levers 72. Adjustable nuts 91 are threaded upon the lower ends of the shafts or rods 87 and the coil springs 89 are compressed between the lugs 90 and the nuts 91 to degrees which are regulatable by means of varying the positions of the nuts 91. It will be seen that the springs 89 exert an upward pressure to partially counterbalance the weight of the cylinders 60 and 70 and thus adjust the printing contact of the attachment. The spring action just described may be reversed by appropriate changes in the construction, if the weight of the printing mechanism is less than the desired pressure between the blanket and impression cylinders.

When it is desired to operate the press 15 as a simple bed and cylinder machine, the auxiliary impression may be thrown off by means of manual rotation of the lever 95 which is pivotally secured at 96 upon one of the frames 11 and which causes the eccentric cam 97 to contact with the surface 98 provided upon the extension 77 of one of the rocking levers 72 in order to depress this arm and thus raise the slides 65 sufficiently not only to move the blanket cylinder 70 out of printing contact with the impression cylinder 20 but also to disengage the teeth of the gears 25 and 68. By this movement, the end 81 of the cam lever 79 is moved away from the cam surface 85 and the auxiliary attachment is completely disassociated from the usual operating mechanism of the bed and cylinder press. The position of the principal parts of the auxiliary attachment when the impression is thus thrown off is clearly indicated in Figure 5 of the drawings.

In order to separate the blanket cylinder from the plate cylinder 60 while inking up or for any other reason, the following means are provided. It will be noted that the bearings 100 of the shaft 63, which are carried by the slide 65, are eccentric bearings and are provided with the arms 101. The ends of the arms or levers 101 are connected by the extensible links 102 with the cranks 103 and 104, each secured upon one end of the shaft 105 which extends across the press. The crank 104 upon the near side of the press as seen in Figures 1 and 2 is longer than the opposite crank 103 and is provided with a handle 106 upon its outer end. A latch 108 is pivoted at 109 upon one of the side frames 11 so as to underlie the lever 104 when moved against the stop 110 and to prevent downward movement of this lever. The latch 108 is urged against the stop 110 by means of the spring 111. When it is desired to separate the cylinder 70 from the cylinder 60, the latch is moved to its dotted line position shown in Figure 5, whereupon the lever 104 may be moved downwardly to its dotted line position and the eccentric bearing 100 rotated within the slides 65 and about the blanket cylinder axle 63 so as to move the blanket cylinder to its dotted line position and thus separate it from the plate cylinder 60.

As illustrated in Figure 5, this separation has been effected while the attachment is in its elevated position out of contact with the impression cylinder 20. This separation, however, may be accomplished at any time since the cylinders 60 and 70 bear upon the impression cylinder 20

only by virtue of their own weight, and it will be readily understood that when the lever 104 is rotated while the auxiliary impression is on, the effect will be to raise the plate cylinder 60 from the blanket cylinder 70 together with the associated slides 65, levers 62, etc. It is to be noted that when the lever 104 is held in place by the latch 108 as shown in full lines in the various figures of the drawings, the rise and fall of the cylinders 60 and 70 during the normal operation of the attachment has no appreciable effect in rotating the eccentric bearing 100. The length of the connection 102 is so great in proportion to the extent of vertical movement of the attachment, and the angular movement of the eccentric bearing 100 necessary to separate the cylinders 60 and 70 is also of such magnitude, that the normal vertical movement of the cylinders during operation does not affect the relation between the individual cylinders.

In order to attain a very fine adjustment of the pressure of the plate cylinder 60 upon the blanket cylinder 70, the turnbuckle 115 is provided in the extensible link 102. By rotation of the turnbuckle 115 the effective length of the links 102 may be altered in order to adjust the rotated position of the eccentric bearing bushing 100 and thus the contact of the plate and blanket cylinders.

The rubber blanket or other offset printing medium 116 is secured upon the blanket cylinder 70 by means of the clamps indicated at 117 and 118, and it will be seen that the blanket 116 does not extend completely around the periphery of the cylinder. Similarly the plate 120 of the plate cylinder is secured by the clamps 121 and 122 and a corresponding gap is provided in this cylinder. At a certain marked position shown especially in Figure 2 of the drawings, the gaps between the ends of the blanket 116 and the plate 120 are disposed in such a position with relation to the feed board 32 and the conveyor arms 33 of the sheet feeding mechanism that sufficient clearance is provided for the projecting ends thereof, especially with respect to the front stop 40, so that the board 32 and the conveyor arms 33 may be raised to permit access to the inking mechanism 19 or other portions of the press. The arc of movement of the outermost portion of the feeding mechanism, represented by the front stop or guide 40, is indicated by the line 123, that of the sheet detector 36 by the line 123', and the path of the extreme end of the feed board 32 is shown at 124.

The inking mechanism for the auxiliary printing attachment will now be described. The upstanding bracket portion 125 is provided on each of the side members 11 of the attachment and is designed to provide a stationary support for the ink fountain 126 within which rotates the ink fountain roll 127. A ratchet wheel 128 is secured to the fountain roll and is driven by the ratchet 129 provided on the rocker 130 actuated by the link 131, which is operatively connected to a suitable cam or other power driven mechanism not shown. A ductor roll 133 is provided with an axle 134 carried in the U-shaped bearings 135 on the arms 136 which are pivoted at 137 to the bracket 138 carried by the bracket portions 125 of the side frames 11. The rocking ductor roll carrying lever 136 is intermittently actuated at the proper intervals by the link 139 which is also driven by suitable means not illustrated. A rider roll 140 retained by the latches or hooks 141 is adapted to secure the ductor roll 133 within its bearings. The ductor roll, as in the usual arrangement, 75

is designed to transfer the ink from the fountain roll 127 to the vibrator roll 144. This vibrator roll is carried by the bracket 145 which is secured as at 146 to the vertically reciprocating slide block 65. Thus the vibrator roll and its associated mechanism are caused to follow the movements of the plate cylinder. The longitudinally reciprocating movements of the vibrator roll are effected by means of the lever 148 which is pivoted at 149 to the bracket 145. One end of the lever 148 is guided within a cam slot 150 provided in a sleeve 151 carried by the plate cylinder axle 62. The opposite end of the lever 148 is provided with means engaging a circular groove in the member 152 carried by the shaft 153 of the vibrator roll. It will be readily seen that by this arrangement an endwise movement of the vibrator roll 144 is attained. The brackets 145 upon opposite sides of the attachment may be secured together by means of a tie rod 155. Rider rolls 157 and 158 are applied to the vibrator roll 144, the rolls 158 being carried by the bearing member 159 which may be secured by the nut 160 at suitable points along the slot 161 so as to equalize the pressures of the rolls 158 against the vibrator roll. Form rolls 165 are provided and suitable means for securing them to the bracket 145 may comprise the trunnions 166 which are secured in the slots 167 as by means of the nuts 168. By this means the form rolls 165 may be disposed so as to be equally spaced from the vibrator roll 144 by plate cylinder 60.

The water roll mechanism for properly dampening the plate on the plate cylinder 60 is preferably arranged as follows. A water roll 170 is provided with an axle 172, which rotates in the bearings 173 carried by the bracket 175 which is in turn secured to the upwardly projecting arm 176 of the side frames 11. The water roll dips into the water pan 174. A pulley 177 is secured to the axle 172 of the water roll and is adapted to be driven by the belt 178 which is trained around the driving pulley 179 carried by the plate roll axle 62. An idler pulley 180 carried by the pivoted arm 181 is adapted to take up the slack in the belt 178 as the plate cylinder 60 rises. A ductor roll 183 is carried by the arms 184 which are pivoted at 185 to the side frame members. A crank 186 is secured to the arms 184 and is connected by means of the link 187 with a pin 188 eccentrically mounted with respect to the cam shaft 35 carried by the sheet feeding end 18 of the press. A lost motion connection between the lever 186 and the link 187 is provided by means of the slot 189. By this means the ductor roll 183 is intermittently moved from the water roll 170 to the plate contacting roller 190. This roller 190 is adapted to reciprocate vertically within the elongated U-shaped bearings 191 carried by the bracket 192 secured to the side frame 11, during movement of the plate cylinder.

From the foregoing description, it will be readily apparent that the greater portions of the inking and dampening devices are carried by the slides 65 so as to move vertically with the plate slides 65 and blanket cylinders 60 and 70 and that the stationary fountain portions of these devices are intermittently placed in communication with the fountain mechanism by means of the ductor rolls 133 and 183.

The embodiment illustrated in Figure 6 of the drawings comprises only a plate cylinder 270 together with its supporting side frames or bracket 211 and its operating mechanism which will now be described. The axle or shaft 263 of the plate cylinder is mounted in bearings carried by the

blocks 285 which may reciprocate vertically within the frames 211. Levers 272 are pivoted to the cross shaft 274 and are each provided at one end with an elongated slot 275 within which is received the pin 276 projecting from each of the slides 285. The extended arm 277 of one of the levers 272 is operatively connected by means of link 278 with a cam (not shown) corresponding to that designated 85 in the embodiment previously described. The arm 277 is provided with a recess 290 within which is seated a coil spring 289 which surrounds the stud or rod 287 secured as at 288 to one of the side members 211. A spring stop 291 may be adjustably positioned upon the rod 287 to control the degree of compression of the spring 289. This spring arrangement is adapted to regulate the degree of pressure between the impression cylinder and the auxiliary plate cylinder 270.

The impression may be thrown off by means of the hand lever 295 which is pivoted at 296 and adapted to operate the cam 297 which bears against the surface 298 on the arm 277. Rotation of this cam 298 will raise the cylinder 270 together with its driving gear (not shown) out of operative contact with the impression cylinder 20 and its driving gear in a manner similar to that described in connection with the device illustrated in Figures 1-5 of the drawings.

An ink fountain 226 is supported by an upstanding portion 225 of the side frames 211 and a fountain roller 227 is indicated somewhat diagrammatically in Figure 6 and is operated by such well-known mechanism as, for example, the pawl and ratchet device shown in Figure 2. A ductor roll 233 is carried by the arms 236 pivoted at 237 and its axle 234 is retained within its bearings 235 as by means of the latch 241. The crank 240 is also secured to the shaft 237, around the axis of which the levers 236 swing, and the link 239 is adapted to be operated by suitable cam or other mechanism to move the ductor roller 233 between the fountain roll 227 and the vibrator roll 244. The vibrator roller is carried by the shaft or axle 253 for rotation in bearings 245 supported by the upstanding bracket portions 245 of the sliding blocks 285. The vibrator roll 244 is reciprocated longitudinally by means of the lever 248 pivoted at 249 to the bracket 245. A projection 250 is provided on the lower end of the lever 248 and is adapted to be guided in a cam groove provided in the sleeve 251 secured upon the axle 263. A projection 252 is formed upon the upper end of the lever 248 and is received within a circular groove provided in the member 254 carried by the axle 253 of the vibrator roll. A pair of rider rolls 258 is carried in adjustable bearings 259 and rotates in contact with the vibrator roll 244. Form rolls 265 are carried in bearings 266 which may be adjusted by suitable means diagrammatically illustrated at 268 so as to effect the proper contact between the vibrator roll 244 and the plate cylinder 270.

The plate carried by the cylinder 270 is provided with a suitable gap or cut-away portion to provide clearness for the sheet feeding mechanism just as in the embodiment previously described.

It will be understood that any desired form of printing impression may be accomplished by the bed 17 of the press whether relief, intaglio, or planographic; and that, in the case of two color work, any color may be applied by either the bed or the auxiliary attachment, although, in general, the bed form may be employed for

black typography and the auxiliary offset attachment for applying designs in color. Similarly the plate cylinders which have been described may be arranged for printing by any of the named 5 processes which are applicable thereto and the blanket cylinder, of course, is employed to effect offset printing.

It is also within the purview of the present invention to provide eccentric cranked bearings for 10 either the plate or the blanket cylinders and means for rotating such bearing to separate the cylinders by either lowering the blanket cylinder as described, or raising the plate cylinder.

It is understood that various changes and 15 modifications may be made in the embodiments herein illustrated and described without departing from the scope of the invention as defined in the subjoined claims.

Having thus described the invention, what is 20 claimed as new and desired to be secured by Letters Patent is:

1. In combination with a printing press of the bed and cylinder type, an auxiliary printing attachment comprising a pair of side frames adapted 25 to be secured to the frame of the press and to extend upwardly above the same, a printing cylinder having the usual opening in its peripheral surface mounted in said side frames for vertical bodily movement therein and disposed above the 30 impression cylinder of the press, means for effecting said bodily movement of the printing cylinder to make printing contact with said impression cylinder, and paper feeding mechanism pivotally mounted at one end of the press and terminating adjacent the impression cylinder, 35 said opening in the peripheral surface of said printing cylinder providing clearance for the end of the feeding mechanism when it is raised about its pivot for gaining access to the portions 40 of the press beneath the same.

2. In combination with a printing press having an impression cylinder, an auxiliary printing attachment comprising a pair of side frames secured to the press and projecting above the same, bearing supporting frames mounted for vertical reciprocation in said side frames, bearings in 45 said supporting frames, a printing cylinder carried by said bearings and disposed above said impression cylinder, means for moving said printing cylinder into and out of printing contact with said impression cylinder, and inking mechanism for said printing cylinder carried by said bearing supporting frames and adapted to reciprocate therewith.

3. In combination with a printing press having an impression cylinder, an auxiliary printing attachment comprising a pair of side frames secured to the press and projecting above the same, bearing supporting frames mounted for vertical reciprocation in said side frames, bearings in 50 said supporting frames, a printing cylinder carried by said bearings and disposed above said impression cylinder, means for moving said printing cylinder into and out of printing contact with said impression cylinder, vibrator and form rollers for inking said printing cylinder carried by said bearing supporting frames and adapted to reciprocate therewith, an ink fountain and fountain roller carried by said side frames, and a ductor roller pivotally carried by said side frames and operable to transfer the ink from said stationary fountain roller to said reciprocable vibrator roller.

4. In combination with a printing press having 55 an impression cylinder, an auxiliary printing at-

attachment comprising a pair of side frames secured to the press and projecting above the same, bearing supporting frames mounted for vertical reciprocation in said side frames, bearings in said supporting frames, a blanket cylinder carried by said bearings and disposed above said impression cylinder, a plate cylinder also carried by bearings in the supporting frame and disposed adjacent said blanket cylinder, means for moving said cylinders as a unit into and out of printing 10 relation with said impression cylinder, and inking mechanism for said plate cylinder carried by said bearing supporting frame and adapted to reciprocate therewith.

5. In combination with a printing press having 15 an impression cylinder, an auxiliary printing attachment comprising a pair of side frames secured to the press and projecting above the same, bearing supporting frames mounted for vertical reciprocation in said side frames, bearings in said supporting frames, a blanket cylinder carried by said bearings and disposed above said impression cylinder, a plate cylinder also carried by bearings in the supporting frame and disposed adjacent said blanket cylinder, means for moving 20 said cylinders as a unit into and out of printing relation with said impression cylinder, vibrator and form rollers for inking said plate cylinder carried by said bearing supporting frames and adapted to reciprocate therewith, an ink fountain and fountain roller carried by said side frames, and a ductor roller pivotally carried by 25 said side frames and operable to transfer the ink from said relatively stationary fountain roller to said reciprocable vibrator roller.

6. In combination with a printing press having 30 an impression cylinder, an auxiliary printing attachment comprising a pair of side frames secured to the press and projecting above the same, bearing supporting frames mounted for vertical reciprocation in said side frames, bearings in 35 said supporting frames, a blanket cylinder carried by said bearings and disposed above said impression cylinder, a plate cylinder also carried by bearings in the supporting frame and disposed adjacent said blanket cylinder, means for moving said cylinders as a unit into and out of printing relation with said impression cylinder, vibrator and form rollers for inking said plate cylinder carried by said bearing supporting frames and adapted to reciprocate therewith, an ink fountain and fountain roller carried by said side frames, a ductor roller pivotally carried by 40 said side frames and operable to transfer the ink from said relatively stationary fountain roller to said reciprocable vibrator roller.

7. In a printing press, in combination, an impression cylinder, a bed cooperating therewith, means for periodically raising and lowering said impression cylinder, a printing cylinder, means for moving said printing cylinder toward and from said impression cylinder to make printing contact therewith prior to printing by the bed 45 during a portion only of its raising and lowering movement.

8. In a printing press, in combination, an impression cylinder, means for periodically raising and lowering said impression cylinder, a print- 50

- ing device comprising a plate cylinder and a blanket cylinder mounted for movement as a unit toward and from said impression cylinder to make printing contact therewith during a portion only of its raising and lowering movement, and means for periodically effecting said movement of said printing device.
9. In a printing press, in combination, an impression cylinder, a printing device comprising a plate cylinder and a blanket cylinder mounted for movement as a unit toward and from said impression cylinder to make printing contact therewith, and means for effecting said movement periodically.
10. In a printing press, in combination, an impression cylinder, a printing member comprising a plate cylinder and a blanket cylinder mounted for straight-line movement as a unit toward and from said impression cylinder to make printing contact therewith, automatic means for effecting said movement periodically, and means for effecting the separation of said plate and blanket cylinders at will.
11. In combination with a printing press of the bed and cylinder type, an auxiliary printing attachment comprising a pair of side frames adapted to be secured to the frame of the press and to extend upwardly above the same, a printing cylinder mounted in said side frames for vertical bodily movement therein and disposed above the impression cylinder of the press, and means for effecting said bodily movement of the printing cylinder to make printing contact with said impression cylinder prior to printing by the bed.
12. In an auxiliary printing attachment for printing presses having an impression cylinder and mechanism for feeding sheets thereto, the latter comprising a driven cam shaft for operating the same, in combination, fountain mechanism disposed in operative relation with the cylinders of said attachment and located above said impression cylinder, said fountain mechanism including a fountain roller and a pivotally mounted ductor roller, linkage connecting said pivoted ductor roller with an eccentric pivot carried by said cam shaft whereby the swinging of the ductor roller is controlled from the sheet feeding cam shaft.
13. In an auxiliary printing attachment of the class described, a stationary frame, a printing cylinder mounted in said frame for vertical reciprocation, a fountain and a fountain roller disposed adjacent said cylinder, means for transferring fluid from said fountain roller to said cylinder, a pulley and belt driving connection between said cylinder and said fountain roller, and means for maintaining the tension in said belt during vertical reciprocation of said printing cylinder.
14. In a printing press of the bed and cylinder type having an impression cylinder and pivoted sheet feeding mechanism at one side thereof, auxiliary printing mechanism including a cylinder disposed adjacent the opposite side of said impression cylinder, and sheet stops and margin rolls adjustably mounted upon the end of said pivoted feeding mechanism.
15. In a printing press of the bed and cylinder type, a multiple cam for operating certain elements of said press in the proper sequence and duration, said cam comprising a cam groove for effecting the vertical reciprocation of the impression cylinder of the press, a lateral cam surface for actuating the sheet grippers of the impression cylinder, a peripheral cam surface for actuating the stripper fingers associated with the impression cylinder, and another peripheral cam surface for effecting the reciprocation of an auxiliary printing cylinder into and out of contact with the impression cylinder.
16. In an auxiliary printing attachment for printing presses, in combination, a supporting frame, bearing supporting members mounted for vertical reciprocation in said frame, bearings in said members, a printing roll carried by said bearings, a lever pivoted intermediate its length to said frame and having one end thereof operatively connected with said bearing supporting members, means connected with the opposite end of said lever to intermittently rock the lever and thus reciprocate said roll into and out of impression contact with the impression member of the press, a cam member rotatably mounted upon said frame adjacent said last named end of said lever, and means for rotating said cam at will to rock said lever to throw off the impression.
17. In an auxiliary printing attachment for printing presses, in combination, a supporting frame, bearing supporting members mounted for vertical reciprocation in said frame, bearings in said members, a printing roll carried by said bearings, a lever pivoted intermediate its length to said frame and having one end thereof operatively connected with said bearing supporting members, means connected with the opposite end of said lever to intermittently rock the lever and thus reciprocate said roll into and out of impression contact with the impression member of the press, and adjustable resilient means between a portion of said frame and said lever for regulating the pressure of the printing contact of said attachment.
18. In a printing press provided with an impression member, in combination, a supporting frame, bearings in said frame, a blanket cylinder carried by said bearings and disposed above said impression member, a plate cylinder also carried by bearings in the frame and disposed adjacent said blanket cylinder, the bearings for said blanket cylinder being eccentric with respect to the axis of said cylinder, crank arms on said blanket cylinder bearings, a lever pivoted to said frame, and links connecting said bearing cranks with said lever, whereby upon movement of said lever said eccentric bearings will be rotated and said blanket cylinder will be separated from the plate cylinder.
19. In a printing press provided with an impression member, in combination, a supporting frame, bearings in said frame, a blanket cylinder carried by said bearings and disposed above said impression member, a plate cylinder also carried by bearings in the frame and disposed adjacent said blanket cylinder, the bearings for said blanket cylinder being eccentric with respect to the axis of said cylinder, crank arms on said bearings, a lever pivoted to said frame, links connecting said bearing crank with said lever, whereby upon movement of said lever said eccentric bearings will be rotated and said blanket cylinder will be separated from the plate cylinder, means for adjusting the lengths of said links in order to regulate the contact pressure between the plate and blanket cylinders, and releasable abutment means for holding said lever in position to maintain the cylinders in contact.
20. In a printing press, in combination, an impression member, a pair of side frames, a vertically reciprocable bearing slide mounted in each of said side frames, two pairs of bearings carried

by said slides, one pair being eccentric, a plate cylinder mounted in one of said pairs of bearings, a blanket cylinder mounted in the other of said pairs of bearings so as to be positioned beneath and normally in contact with said plate cylinder and substantially above said impression member, means for periodically reciprocating said slide so as to move said cylinders as a unit into and out of printing relation with said impression member, cranks on said eccentric bearings and extending vertically therefrom, a pair of levers, each secured upon an end of a rock shaft mounted in said side frames in substantial horizontal alignment with the eccentric bearings, said levers normally being horizontally disposed, links connecting said bearing cranks with said levers whereby upon movement of the latter said eccentric bearings are rotated to effect the separation of said cylinders.

21. In a printing press of the bed and cylinder type having an impression cylinder, sheet feeding mechanism at one side of said cylinder pivoted remotely therefrom for raising movements, auxiliary printing mechanism including a cylinder having the usual opening in its peripheral surface disposed adjacent the opposite side of the impression cylinder and above the same, said auxiliary cylinder being of the same diameter as the impression cylinder, and means to move said auxiliary cylinder to and from said impression cylinder to make printing contact with the impression cylinder prior to printing by the bed, said opening in the auxiliary cylinder providing clearance for the end of said sheet feeding mechanism so that it may be raised about its pivot without disturbing any part thereof.

WILLIAM M. KELLY.
